CONTACT LENS STORAGE CHAMBER

Paul A. Hoogesteger, Penfield, and John Kadlecik,
Macedon, N.Y., assignors to Bausch & Lomb Incorporated,
Rochester, N.Y.

Filed July 22, 1974, Ser. No. 490,536

Term of patent 14 years

Int. Cl. D3—02

U.S. Cl. D57—1 B

FIG. 1

FIG. 2

FIG. 4

FIG. 3

FIG. 1 is a perspective view of a contact lens storage chamber taken from the catch side thereof showing our new design, the top being in an open position;

FIG. 2 is a perspective view of our new design taken from the hinge side thereof, the top being shown in the open position;

FIG. 3 is a bottom plan view thereof; and

FIG. 4 is another perspective view of our new design taken from the catch side thereof showing the top of FIGS. 1 and 2 in a more fully open position.

We claim:

The ornamental design for a contact lens storage chamber, substantially as shown and described.
